UNITED STATES PATENT OFFICE.

WILLIAM H. GOLDING, OF CHELSEA, MASSACHUSETTS.

MECHANICAL MOVEMENT.

SPECIFICATION forming part of Letters Patent No. 267,875, dated November 21, 1882.

Application filed April 1, 1882. (No model.)

To all whom it may concern:

Be it known that I, WM. H. GOLDING, of Chelsea, county of Suffolk, and State of Massachusetts, have invented a new and useful 5 Mechanical Movement; and I do hereby declare that the following is a full and exact description of the same, reference being had to the accompanying drawings, and to the letters of reference marked thereon.

10 This invention is a mechanical movement adapted by means of its peculiar construction to convert a uniform revolution into a reciprocating movement having an interval of rest, as will be fully described hereinafter.

15 In the drawings, Figure 1 represents a side view of a printing-press having my mechanical movement applied thereto; Fig. 2, a rear view, and Fig. 3 a side view, of the same, the latter being partially in section; Fig. 4, a side view, 20 partially in section, illustrating that period in the revolution of the shaft when the interval of rest occurs; Fig. 5, a side view, partially in section, illustrating a position of the movement which is opposite to that shown in Fig. 4, and 25 Fig. 6 a front view of the movement detached from its connections.

30 To enable others skilled in the art to make my invention, I will proceed to describe fully the construction of the same and the manner of its operation.

35 A represents a shaft, suitably supported in any proper bearings, which is adapted in any proper manner to receive revolution from any suitable source of power.

35 a represents a crank formed in the shaft, and B a connecting-rod, by means of which the crank is united to one end of the rocker-beam C, as shown.

40 The connecting-rod, if desired, may be attached to any proper mechanism to which it is desired to impart a reciprocating movement having intervals of rest.

The connecting-rod B, it will be observed, equals or nearly equals the crank-arm in length.

The operation is substantially as follows: 45 Revolution having been given to the shaft A in any proper manner, the rocker-beam or other mechanism attached to the outer end of the connecting-rod receives a reciprocating movement having intervals of rest. This interval 50 of rest occurs once in a revolution at the time when the crank a is in its highest position, as shown in Fig. 4, and results from the fact that the connecting-rod B equals or nearly equals in length the arm of the crank a. From this 55 construction it follows that when the crank is approaching or leaving its highest position the center upon which the lower end of the connecting-rod moves is then nearly coincident with the center of the shaft A, and consequently 60 the rod at this time is simply swung with the crank, instead of being actuated to exert a downward thrust. The exact coincidence of the crank and the connecting-rod in their movement continues only while the two lie in the 65 same vertical plane; but as in approaching and leaving this line the vertical movement of the rod is necessarily small it follows that an appreciable interval of rest is obtained.

Having thus fully described my invention, 70 what I claim as new, and desire to secure by Letters Patent, is—

The mechanical movement described, consisting of the shaft A, crank a, and connecting-rod B, the crank and connecting-rod being 75 equal or nearly equal in length, as and for the purpose set forth.

This specification signed and witnessed this 1st day of March, 1882.

WILLIAM H. GOLDING.
